Attorneys.

UNITED STATES PATENT OFFICE

MELVIN G. BAKER, OF CHICAGO, ILLINOIS, ASSIGNOR TO CHICAGO FORGING & MANUFACTURING COMPANY, OF CHICAGO, ILLINOIS, A CORPORATION OF ILLINOIS

METHOD OF FORMING CONNECTIONS

Original application filed November 7, 1927, Serial No. 231,478. Divided and this application filed May 31, 1928. Serial No. 281,849.

- My invention relates to a method of connecting metal objects and has for one purpose the provision of a method for joining handles and tubes which is particularly applicable to the manufacture of hood latches.
- 5 The present application is a division of my co-pending application No. 231,478, filed on November 7, 1927. Other objects will appear from time to time in the course of the specification and claims.
- 10 I illustrate my invention more or less diagrammatically in the accompanying drawings, wherein—
- Figure 1 is a vertical section through an automobile hood showing my hood latch in locking position;
- 15 Figure 2 is a plan view of the structure shown in Fig. 1;
- Figure 3 is a vertical section through the latch stem and handle and head before being assembled;
- 20 Figure 4 is a section on the line 4—4 of Figure 3;
- Figure 5 is a vertical section similar to Figure 3 showing parts assembled;
- 25 Figure 6 is a section on the line 6—6 of Figure 5;
- Figure 7 is a front elevation of the upper portion of the sleeve;
- 30 Figure 8 is a side elevation of the sleeve;
- Figure 9 is a section on the line 9—9 of Figure 7;
- Figure 10 is a side elevation of the handle partly in section;
- 35 Figure 11 is a vertical section of a variant form;
- Figure 12 is a view similar to Figure 10, of a variant form;
- 40 Figure 13 is a section on the line 13—13 of Figure 12; and
- Figure 14 is a section on the line 14—14 of Figure 12.
- Like parts are indicated by like symbols throughout the specification and drawings.
- 45 A is a portion of an automobile frame, to which may be secured an upstanding rib or abutment member A¹, against which abuts the lower edge B¹ of the hood B when the hood is closed. Fastened to the hood B is a member generally designated as B², which in-
- cludes a downwardly and outwardly inclined cam portion B³, upwardly and outwardly inclined prongs B⁴ separated, for example, by the notch B⁵, a central portion B⁶ which is secured to the hood, B, and a downwardly and inwardly turned bottom portion B⁷. B⁸ are any suitable securing members.
- C is any suitable shaft or pin terminating at the bottom in the square beveled head C¹. C² generally indicates a base member having a frame engaging securing portion C³, through which may pass any suitable securing member C⁴, and the intermediate raised portion formed by the upwardly and inwardly inclined top portion C⁵ and the generally vertical side walls C⁶. C⁷ is a concave, generally spherical flange surrounding the aperture C⁸, through which passes the pin C.
- The latch body proper consists of the cylindrical member D, herein shown as rolled from a single blank and with the single axial seam D¹. The bottom of the cylinder may be formed in any suitable manner to retain the abutment below described. I illustrate the cylinder as being inwardly crimped as at D³ to secure the washer D⁴ which is loose on the shaft C. D⁵ is a washer secured to the upper end of the pin C and D⁶ indicates a coil spring compressed between the two washers. The tendency of such spring is therefore to draw the cylinder D downwardly along the stem C.
- The cylindrical member or seamed tube D is formed with indentations or apertures in its upper portion. I illustrate the horizontal notches or apertures E E¹ situated a slight distance from the top of the tube. The tube may, if desired, be formed with the inwardly turned flanges E². It will be realized that the top of the tube may be formed in a variety of different ways, it being essential that some aperture or indentation or inwardly off-set portion be provided.
- G indicates generally a handle member which includes a finger engaging portion G¹ projecting from one side, and the T lug G², with the cross-bar G³, extending from the other. The intermediate portion G⁴ is provided with a downwardly projecting cylindrical flange G⁵ centrally apertured as at

G⁴ to receive the upper end of the tube D. Prior to the assembly and completion of the latch the portion G⁵ is provided with outwardly projecting lugs or extensions of material overlying or aligned with the apertures E E¹. In assembling the latch any suitable arbor G' may be introduced within the tube and, when the handle member G is in position the lugs or extensions G⁶ are placed between the squeezing jaws G' and are subjected to pressure sufficient to flow the metal of the handle into the opposed indentations or apertures of the tube. The result is a peculiarly complete and permanent attachment of handle to tube, the connection being only severable by the destruction of the handle member or the collapse of the tube. The collapse of the tube is particularly difficult, and in practice is not likely to take place, since the end of the tube is both protected and reinforced by the sturdy surrounding portion G⁵ of the handle. G¹⁰ indicates any suitable lugs or lug member opposed to the cam B² on the hood.

In the operation of the latch it will be understood that when the T lug is between the members B⁴ in the notch B⁵, the outward movement of the latch away from the hood is prevented. As the spring D⁵ draws the cylinder D downwardly along the pin C the lugs G¹⁰ are opposed to the cam B² and to the downward locking movement of the latch is added the resultant lateral thrust against the hood.

In Figure 11 I have shown the cylinder D having the indentation H, instead of slots. Figures 12 to 14 indicate a variation of my method in which I omit the projection G⁴ as shown in Figure 3 and 10 and thus leave an indentation in the exterior of the finally finished member G⁴ indicated as G¹⁵ in Figures 12, 13 and 14.

In particular it will be realized that where in the claims I employ the term "aperture" I wish to be understood as meaning not merely an aperture completely through the tube, but any indentation or off-setting of the tube or the tube surface which will provide an equivalent space into which the metal of the handle may flow.

Whereas I have illustrated means for forcing cold metal into the indentations or apertures of the member D it will be realized that I may obtain an equivalent result by positioning the tube B in a mold and pouring hot metal about it, thereby causing the metal to flow into the apertures and thus to form a permanent engagement with the tube equivalent to that formed by the flowing of cold metal into the tube.

I claim:

1. The method of forming a connection between a tubular body and a surrounding metallic body which includes forming an aperture in the end of said tubular body, inserting said end within the member to which

it is to be secured, inserting an arbor within the tubular member, directing pressure inwardly against the surrounding member and thereby forcing a portion of the metal thereof into said aperture and removing the arbor.

2. The method of forming a connection between a tubular body and a surrounding metallic body which includes forming an aperture in the end of said tubular body, inserting said end within the member to which it is to be secured, inserting an arbor within the tubular member, directing pressure inwardly against the surrounding member and thereby forcing a portion of the metal thereof into said aperture and removing the arbor, and thereafter smoothing the outer surface of said surrounding member.

3. The method of forming a connection between a casting and a hollow tubing which includes providing in the casting an aperture conforming to the exterior surface of the hollow tube, aperturing the sides of the hollow tube, adjacent the end which is to penetrate the casting, inserting it within said casting and applying pressure to the exterior of said casting to force the metal thereof into such aperture.

4. The method of forming a connection between a casting and a hollow tubing which includes providing in the casting an aperture conforming to the exterior surface of the hollow tube, aperturing the sides of the hollow tube, adjacent the end which is to penetrate the casting, inserting it within said casting and applying pressure to the exterior of said casting to force the metal thereof into such aperture, while positioning an arbor within the tube to prevent its collapse during the application of pressure, and subsequently withdrawing the arbor.

Signed at Sawyer, county of Sawyer and State of Wisconsin, this 21st day of May, 1928.
